UNITED STATES PATENT OFFICE.

BENJAMIN B. ROBLEY, OF BUFFALO, NEW YORK.

MIXER AND PRIMER.

1,151,047.

Specification of Letters Patent. Patented Aug. 24, 1915.

Application filed August 27, 1913. Serial No. 786,929.

To all whom it may concern:

Be it known that I, BENJAMIN B. ROBLEY, a citizen of the United States, residing at Buffalo, in the county of Erie and State of 5 New York, have invented new and useful Improvements in Mixers and Primers, of which the following is a specification.

This invention relates to mixers and primers, the object of the invention being 10 to provide a combination device of the character referred to which is applicable to any internal combustion motor, the said device being used in connection with the intake pipe or intake manifold of the engine, primarily for the purpose of supplying fresh 15 air to the mixture at a point between the carbureter and the combustion chamber or chambers, in the desired quantity, and also designed to provide for the introduction of 20 gasolene or other primary agent into the system to facilitate the starting of the engine.

With the above and other objects in view, the invention consists in the construction, 25 combination and arrangement of parts, as will hereinafter be more fully described, illustrated and claimed.

In the accompanying drawings: Figure 1 is a side elevation showing the combined 30 mixer and primer of this invention. Fig. 2 is a diametrical section through the same showing also a portion of an intake manifold.

The combined mixer and primer contemplated in this invention embodies a cup-shaped hollow body 1 forming an air chamber 2 therein to which air is admitted through an inlet hole 3 shown as formed in one side of the chamber and extending 40 through the wall of the body. At its lower end the body is reduced in size to form a relatively small neck 4 in which is a tapering valve seat 5 the purpose of which will appear. The neck is then enlarged to form 45 a nut face 6 to facilitate the screwing the device as a whole into and out of place in a manifold indicated at 7 or in the intake pipe between the carbureter and manifold or combustion chamber. For this purpose the 50 device is provided with a threaded tubular end portion 8.

9 designates a threaded plug or cap which is screwed into the upper internally

threaded end of the body 1, said plug being movable to give access to the air chamber. 55 Threaded through the center of the plug or cap 9 is a needle valve stem 10 the inner end of which is pointed or tapered as shown at 11 to closely fit the correspondingly tapered seat 5 above referred to. At its outer end 60 the needle valve is provided with an angularly extending handle 12 provided for turning the threaded stem of the needle valve in the cap or plug 9.

13 designates a lock nut of the thumb or 65 wing type so as to fix the adjustment of the needle valve in accordance with the demands of the engine.

Before starting the engine, the desired 70 quantity of gasolene or other hydrocarbon is injected through the opening 3 and finds its way into the intake pipe or manifold as the case may be and from thence into the combustion chamber or chambers. After the engine is started, the needle valve is adjusted to admit the necessary quantity of air 75 to provide for the best running speed and power of which the engine is susceptible. In actual practice, the device hereinabove described has been found to add from 80 twenty-five to forty per cent. to the power of the engine or to effect a corresponding reduction in the amount of gasolene or fuel oil used. An engine equipped with the device hereinabove described runs with 85 greater freedom, at a higher speed and is far more efficient in the power developed.

What I claim is:

The combination with the intake manifold of an internal combustion engine, of a 90 combined mixer and primer embodying a cup-shaped body forming an air and liquid chamber provided with an inlet hole in the side wall thereof and an outlet passage in the bottom thereof, a valve seat in the bottom of said chamber at the inner end of said outlet passage, a detachable cap at the opposite end of the chamber, a needle valve threaded through said cap, and locking 95 means for said valve stem. 100

In testimony whereof I affix my signature in presence of two witnesses.

BENJAMIN B. ROBLEY.

Witnesses:

J. T. WALLIS,
PETER C. CROSSETT.
